UNITED STATES PATENT OFFICE.

JAPHET S. CUSSON, OF FREDONIA, NEW YORK.

DESIGN FOR A PAD FOR HARNESS BREAST-STRAPS.

SPECIFICATION forming part of Design No. 20,277, dated November 11, 1890.

Application filed September 18, 1890. Serial No. 365,443. Term of patent 7 years.

To all whom it may concern:

Be it known that I, JAPHET S. CUSSON, a citizen of the United States, residing at Fredonia, in the county of Chautauqua and State 5 of New York, have invented and produced a new and original Design for Pads for Harness Breast-Straps; and I do hereby declare the following to be a full, clear, and exact description of the same, reference being had to

10 the accompanying drawings, forming a part thereof.

Figure 1 is a plan view of my harness breast-strap pad, showing my design. Fig. 2 is an edge view of the same; and Fig. 3 is a cross-15 sectional view of the design, these three views being deemed necessary to illustrate my design.

The leading feature of my design consists in a flat portion having parallel edges, which 20 are scalloped transversely and tapered longitudinally, and terminates in abrupt unscalloped ends. Viewed edgewise each edge represents numerous rounded surfaces, all being equal in length.

25 A designates the body of the breast-strap pad, which may be made of any suitable ma-

terial; but I prefer felt. This breast-strap pad presents scallops *a* on its longitudinal edges, and when viewed edgewise the pad tapers from the central portion outwardly on either side 30 to the extreme ends *b b*, the pad being thickest in the middle, as represented in the edge view, Fig. 2. At given points certain pieces or straps are applied. These straps may or may not be used.

35 In my improved design it will be seen that there are loops applied to the pad. These loops constitute one of the essential features of my design. They are straps having buckles arranged in proper order of the design; or instead of the buckles simply loops can be substituted, if preferred.

40 What I claim is—

45 The design for breast-strap pads herein shown and described.

In testimony whereof I affix my signature in presence of two witnesses.

JAPHET S. CUSSON.

Witnesses:

WILLIAM S. RANN,
FRED W. PLATO.
